US0D1017240S

(12) **United States Design Patent** (10) **Patent No.:** **US D1,017,240 S**
(45) **Date of Patent:** **** Mar. 12, 2024**

(54) **FLY ROD HOLDER**

(71) Applicant: **SHENZHEN BANMIAO TECHNOLOGY CO., LTD.**, Shenzhen (CN)

(72) Inventor: **Hengxu Xia**, Shenzhen (CN)

(73) Assignee: **SHENZHEN BANMIAO TECHNOLOGY CO., LTD.**, Shenzhen (CN)

(**) Term: **15 Years**

(21) Appl. No.: **29/896,927**

(22) Filed: **Jul. 10, 2023**

(51) **LOC (14) Cl.** **03-01**

(52) **U.S. Cl.** **D3/260**
USPC **D3/260**

(58) **Field of Classification Search**

USPC D3/260; D22/134, 147, 148, 260
CPC A01K 97/10
See application file for complete search history.

(57) **CLAIM**

The ornamental design for a fly rod holder, as shown and described.

DESCRIPTION

FIG. 1 is a perspective view of a fly rod holder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the fly rod holder where the fly rod holder is in a fully open state.

1 Claim, 9 Drawing Sheets
